UNITED STATES PATENT OFFICE.

LOUIS ILLMER, OF CORTLAND, NEW YORK.

FUEL PUMP FOR INTERNAL-COMBUSTION ENGINES.

Application filed December 7, 1921. Serial No. 520,493.

To all whom it may concern:

Be it known that I, LOUIS ILLMER, a citizen of the United States, and a resident of Cortland, in the county of Cortland and the State of New York, have invented certain new and useful Improvements in Fuel Pumps for Internal-Combustion Engines, of which the following is a specification.

My invention relates particularly to improvements in high pressure injection pumps for so-called solid injection liquid fuel engines, and its object is to provide a device which without the use of compressed air, maintains a high injection velocity through the spray nozzle of an internal combustion engine regardless of the engine speed.

The primary aim of this device is to break up the injected liquid fuel into a finely atomized formation so that the increased surfacing will admit of rapidly and more perfectly mixing such injected fuel with all the available cylinder air, thereby improving the combustion process and augmenting the power capacity of a given engine cylinder.

Another object is to provide a directly reversible fuel pump that will run an injection oil engine equally well in either direction of rotation without resorting to a reverse gear for shifting the phase of the plunger movements in relation to the engine piston movements.

Still another object is to provide a device as above described in which one pump plunger running at a multiple speed ratio with respect to the engine crankshaft is capable of successively serving a plurality of power cylinders.

The present invention also embodies improvements in the spring drive or plunger impulsing element of this type of fuel pump, and in the co-ordination of the required valve and spray nozzle parts with respect to the fuel pump, and it furthermore comprises a spare pump means and various other features of structure and organization, all of which will be set forth in detail hereinafter.

Reference is had to the accompanying two sheets of drawings which illustrate examples of various forms of my invention; like characters of reference indicate like parts in the several views, and in which drawings:

Fig. 1., is an elevational end view of my impulsion fuel pump equipt with a reduc-

tion gear for actuating the discharge valves thereof.

Fig. 2., is an elevational side view of the pump illustrated in Fig. 1., showing a partial sectional view of the pump block as taken on the line 1—1 of Fig. 1.

Fig. 3., is a sectional detail of the mechanically operated discharge valves as taken on the line 2—2 of Fig. 2.

Fig. 4., is an elevational view of the assembled pump in section as taken along the line 3—3 of Fig. 3.

Fig. 5., represents a detail of a toggle linkage adapted to adjust the regulation and to control the reversing of the pump shown in Fig. 2.

Fig. 6., is a sectional view through the power cylinder as taken along the line 6—6 of Fig. 7.

Fig. 7., represents an elevational side view of a four-stroke oil engine equipt with my fuel pump, in which the multiple discharge valves of the pump are independently actuated from the camshaft of the engine.

Fig. 8., shows a sectional detail of the combined spray and discharge valve casing as taken along the line 4—4 of Fig. 6.

Fig. 9., represents a further detail of Fig. 8., as taken along the line 5—5.

Fig. 10., represents a control gear detail for cutting out of service a defective main fuel pump and in its stead of quickly throwing into service a duplicate or spare unit.

Fig. 11, is a plan view of Fig. 10, showing the cross-connected delivery pipes between the main and the spare pumping units.

Referring first to Figs. 2 and 4., the numeral 10 represents a flanged pump bracket which is intended to be fastened to a convenient part of the engine. This bracket is provided with projecting ribs 10^a carrying a pair of split bearings 11 for the purpose of mounting the driveshaft 12, which shaft is intended to be driven from the engine which it serves. The eccentric 13 mounted upon the driveshaft 12, engages with the wristpin 13^a and imparts reciprocating movement to the spring casing 14 in synchronism with the engine piston movements, and these parts taken together, constitute the rigid actuating part of the impulsion fuel pump.

The said casing 14 is slidably mounted within the guide 15 which is preferably

formed integral with the bracket casing 10. The plunger drive part 16 having a flanged portion 16^a and an enlarged collar 16^b, is slidably mounted with respect to the casing 14. Thrusting between the flange 16^a and the lower casing shoulder 14^a is a relatively powerful primary drive spring 17^a, while above said flange is mounted a similar secondary spring 17^b thrusting against the shoulder lug 14^b and set to act in opposition to the primary spring.

These opposed drive springs are intended to be forced into place under a considerable initial tension, so that the flange 16^a is normally made to assume the relatively fixed balanced position with respect to the casing 14 that is indicated by dotted lines in Fig. 4., and it will be seen that the resilient member 17^a and 17^b serve as an impulsion drive for the plunger parts 16^a and 16^b. The extent to which the drive flange 16^a is intended to be displaced out of its balanced position with respect to the casing 14 is indicated in Fig. 4., by the distance marked 25 "K". When the flange 16^a is thus fully displaced as indicated by its full lined position, the spring 17^a will be carrying substantially the entire load imposed upon the pump plunger while the secondary spring 17^b will 30 be partially expanded but is intended to still retain some of its initial counter thrust. The force required to displace the drive flange 16^a out of its balanced position will therefore be measured by the difference of 35 the opposing spring thrusts acting thereon, and such average displacement force when multiplied by displacement distance will be a measure of the impulsion energy that may be stored and subsequently released for 40 impelling the driven plunger part forward with respect to the casing movement.

The pump block 18 is preferably made of machinery steel and securely fastened to a projecting portion of the bracket casting 10. Within this block is mounted the reciprocating plunger 19, which is suitably sealed against pressure leakage by means of the packing 20 and this packing may be adjusted by means of the gland 21. The 50 plunger 19 is intended to work reasonably free through said packing so as not to interfere unduly with the action of the impulsion drive springs. The plunger is fastened into the drive part 16 so as virtually to become an integral part thereof.

As is best shown in Fig. 2., the pump block 18 is further provided with an automatic suction valve 22 which takes its fluid supply through the feed pipe 23. The pump 60 block is furthermore provided with a pair of discharge valves 24^a and 24^b, either of which positively controls the pump delivery. The said suction valve and the set of discharge valves communicate with the plunger bore through the common passage

25 drilled in the block 18 and this constitutes the pump chamber.

The discharge valves 24^a and 24^b are preferably of the check type opening inwardly into the pump chamber as shown, and these 70 valves are alternately opened against chamber pressure in phase or synchronism with the rigid actuating gear movements that reciprocate the casing 14. The mechanism for mechanically opening said discharge 75 valves comprises a cam disc 26 which is centered by the cam spindle 27 and slidably mounted for lateral movement along the axis thereof. The spring 27^a normally thrusts the cam disc against the bracket casting 10 into the position shown by full lines in Fig. 2. The cam disc 26 is provided with a raised part 26^a and an opposite depressed part 26^b, while between these parts the cam face is of circular contour. This 80 cam is driven at half speed with respect to the drive shaft 12 by means of a set of spur gears 28^a and 28^b, the latter being shown as an integral part of the cam disc 26.

This cam engages with a lever part 29 mounted on the fulcrum 29^b. The lever toe 29^a is held in engagement with the cam face by a relatively stiff spring 30 and the movement imparted to the lever 29 is transmitted 85 to the actuating spindles of the discharge valve by the tie rod 31.

The pair of bodies 32^a and 32^b which respectively mount the discharge valves 24^a and 24^b, are of similar construction except that they are fashioned as right and left hand bodies as will appear from Fig. 3. Referring in detail to the sectional assembly of the removable left hand discharge valve shown in Fig. 2., the body part 32^a is provided with a threaded shank portion having an encircling ground seat 33^a engaging with the pump block 18 and held in place by the threaded shank nut 34^a. The shank of this nut is enlarged at its lower end to form the annular seat 35^a which also thrusts against the block 18 but acts counter to the thrust of the body seat 33^a to make a breakable hydraulic joint for the convenient removal of the body part 32^a. The shank nut 34^a is furthermore recessed to receive the spring 36^a which normally holds the discharge valve 24^a against the seated body part 32^a. The small hole 37^a shown in Fig. 2., and the hole 37^b shown in Fig. 3., serve 110 to place the respective shank nuts in communication with the pump chamber 25 so as to become a part thereof.

Within the body part 32^a, an actuating spindle head 38^a is rotably mounted and this is slotted to constitute the lip 39^a which engages with the stem of the discharge valve 24^a. This spindle is further provided with a reduced stem part 40^a extending through the tubular nut 41^a, the head of 115 120 125 130

which nut bears tightly against the body 32^a to make an hydraulic joint therewith. The spindle shoulder 44^a serves as a ground annular seat which bears against the inner end 5 of the tubular nut 41^a and allows the spindle 38^a to revolve with respect to the body part 32^a. The equalizing hole 45^a throws the pump discharge pressure against the rear face of the spindle head 38^a for the purpose 10 of maintaining a pressure tight joint at the seat 44^a.

The outer or free end of the spindle stem 40^a is provided with a bell crank 42^a, one arm of which engages with the tie rod 31 15 while the other arm connects with the adjacent rocker 42^b through the strap 43, whereby both spindles 40^a and 40^b are positively actuated from the cam disc 26. As shown in Fig. 3, the discharge check valve 20 24^a is preferably offset from the axis of the spindle 40^a and slidably mounted with respect to the body part 32^a to form a pressure tight control for the oil discharge from the pump chamber. The lip 39^a of the oscillating spindle periodically engages with the 25 free end of the stem of valve 24^a for the purpose of opening the latter. The spindle head 38^a is also provided with a small hole drilled crosswise of its axis to maintain 30 communication between the discharge valve and the nozzle pipe 46^a; and in a twin cylinder engine this pipe leads directly to the spray nozzle of one power cylinder while the similar pipe 46^b is intended to serve the 35 other cylinder.

Referring now to the control means for regulating the oil discharge from the fuel pump to the engine cylinders, the block 18, as best shown in Fig. 4., is provided with a 40 bypass valve 47 having a seat 47^a formed in a recessed portion of the block 18. Mounted within such block recess is a spring 48 which thrusts against the plug nut 49 and serves to close the bypass valve. This valve is 45 placed in communication with the plunger bore and the rest of the pump chamber through the passage 50. The stem of the bypass valve 47 is undercut just below its seated head part so that when open, the 50 valve may freely vent the pump chamber into the return pipe 51, which may be connected to discharge into the supply pipe 23 if so desired. The stem of the bypass valve 47 is extended downward through the pump 55 block 18 and is sealed against leakage by the packing 52, the free end of the stem being formed into a tip 47^b to engage with the floating lever 53. One of the lever ends rests upon the plunger drive collar 16^b and 60 is reciprocated thereby, while the other lever end is fulcrumed in the stanchion 54 by means of the pin 54^a. This stanchion is slidably mounted within a portion of the bracket casting 10 and rests upon the control 65 shaft 55, which is also slidably mounted but

set to move normally with respect to the stanchion axis.

As is best shown in Fig. 2., the control shaft is provided with an actuating pin 55^a and a recessed cam face 55^b adapted to lift 70 or lower the stanchion 54 in accordance with the lateral adjustment given to the sliding shaft 55. After the fulcrum pin 54^a has been raised to a predetermined height, the flat portion of the cam face 55^b comes into 75 action and this allows the control shaft 55 to be further shifted without augmenting the stanchion lift. When the shaft assumes this critical position, the overhanging shaft toe 55^c will have engaged with the edge of the 80 gear 28^b. Since this gear together with the cam disc 26 is slidably mounted on the spindle 27, any further movement of the control shaft will ultimately cause the cam disc 26 to be shifted into the dotted position indicated in Fig. 2., without however throwing out of mesh the gears 28^a and 28^b. The raised cam lug 26^a as also the depressed part 26^b of the cam disc 26 are made relatively 85 short as measured lengthwise of the spindle 27, so that when shifted into the dotted position, the lever toe 29^a will be riding on a perfectly round portion of the cam disc 26, and no movement will be imparted to the tie rod 31, thus disengaging the actuating 90 gear of the positively operated discharge valves 24^a and 24^b.

Referring now to Fig. 5., this detail shows a toggle link control mechanism for adjustably setting the position of the shaft 55. 100 The notched sector 56 is fixedly mounted on the fulcrum pin 57, while pivotably mounted thereon is a bell crank 58 comprising a latched adjusting lever and a link arm for the actuating toggle. The link strap 59 engages with the pin 55^a so that any movement of the adjusting lever to either side of its central or stop position will cause the control shaft 55 to be drawn toward the fulcrum pin 57. When the control shaft is set 105 in the aligned toggle position as shown in Fig. 5., the toe 55^c will cause the discharge valve gear to be disengaged from the actuating cam 26 in the manner previously set forth.

Having thus described in detail the parts of the preferred form of my invention, the manner in which said parts operate is as follows:

Assuming the parts to be in the position 120 show in Figs. 1 to 4 inclusive and with the spring casing 14 moving upward and the eccentric 13 approaching its upper or inner dead center position when rotating in the direction indicated by the arrows, then the plunger 19 will during its preceding downward stroke already have sucked a charge of oil into the pump chamber 25 through the suction valve 22. During such suction stroke, the negligible resistance of the 125

plunger packing allows the drive flange 16^a to remain in substantially its balanced position with respect to the casing 14. As soon however, as the eccentric 13 passes its lower or outer dead-center position and begins to lift the casing 14, the resulting reversal of movement promptly closes the automatic suction valve 22 and thereafter this as well as the other pump valves remain closed until such time as the eccentric 13 has almost completed its discharge stroke and reached a predetermined position as indicated in Fig. 4., by the letter "a".

Since during the stated period, none of the oil is allowed to discharge from the pump chamber, the effect of such initial lifting of the casing 14 is to hold the driven plunger part 16 in a virtually stationary position except for plunger slip while the flange 16^a is being displaced from its balanced position against the combined resistance of the impulsion springs 17^a and 17^b by an amount of deflection indicated in Fig. 4., by the letter "K," which in the case illustrated is made approximately equal to the full eccentric travel. The displacement "K" of the impulsion drive may be termed "kick" and its action is essentially the same as that more fully explained in my co-pending patent application Serial No. 229,556. Such displacement not only stores impulsion energy within said drive springs but also sets up a relatively high hydraulic pressure throughout the pump chamber passages as well as behind both of the closed discharge valves 24^a and 24^b.

When the eccentric 13 approaches the given position "a," the cam lug 26^a engages with the lever 29^a to lift the tie rod 31 and shift the tie strap 43 into its leftward position "b" which in turn opens the discharge valve 24^a against the existing chamber pressure. This valve controls the release of the stored energy in the impulsion drive and when opened, the pump plunger is immediately impelled forward with respect to the movement of the casing 14, and the pump sends forth its delivery through the pipe 46^a and thence to the spray nozzle of the engine cylinder. The released plunger will surge forward as rapidly as the unbalanced spring force is capable of crowding oil through the restricted area of the spray nozzle and it will be seen that the impulsion drive serves to maintain high nozzle velocity until the balanced or equilibrium position between the primary and secondary drive springs is again restored.

It is intended that the drive springs be made sufficiently powerful to completely inject the fuel into the engine cylinder during a comparatively small angular travel of the eccentric and prior to the closure of the discharge valve 24^a.

After completing the "kick" action as explained, the suction valve 22 is again opened by the return or downward stroke of the plunger and a fresh charge of oil is drawn into the pump chamber. During the next succeeding upward travel or discharge stroke of the casing 14, this will again cause the impulsion spring drive to be displaced and charged with energy in the manner previously described, and by the time the eccentric 13 reaches the position "a" for a second time, the cam depression 26^b located directly opposite to the cam lug 26^a which is running at half-speed with respect to the drive shaft 12, will have come into engagement with the lever toe 29^b, which in turn allows the spring 30 to shift the strap 43 into its rightmost position "C" and open the discharge valve 24^b without however, disturbing the adjacent seated valve 24^a. As a result, the pump will now deliver through the pipe 46^b and send forth oil to the spray nozzle of the alternate cylinder which is intended to be operated from a crank set at a suitable angle with respect to the crank used for the cylinder that is served by the discharge valve 24^a.

As applied to the case of a twin cylinder four-stroke oil engine, the pump eccentric 13 may be driven at crankshaft speed when the valve gear for the adjacent power cylinders is set to alternately fire the cylinder charges. When the directly reversible fuel pump shown in Figs. 1 to 4., is made to serve such an engine, the position of the cam disc 26 is preferably set in phase or alignment with the common crank position of the engine, such that the cam lug 26^a will raise the tie rod 31 to its maximum lift at about the same instant that the crankshaft passes its inner dead center position. The twin discharge valves will then be properly timed to open and alternately inject fuel a little in advance of the dead center position of the respective engine cylinders.

The reversibility of this fuel pump without resorting to any shifting gear for the drive mechanism constitutes an important feature of the present invention. For the setting indicated, the cam disc 26 used for alternately opening the discharge valves 24^a and 24^b is still correctly timed to inject a little in advance of the proper dead center position of the respective twin power cylinder when running the engine in either direction of rotation. It will be seen therefore that the impulsion plunger drive makes it possible to carry the pump eccentric up close to its dead center position prior to discharge valve opening and the energy that has in the mean time been stored within such drive may still be instantly released by opening the discharge valve to impart a rapid "kick-like" movement to the plunger.

In this improved pump, the plunger movement is made entirely independent of the slow moving actuating gear parts, a feature which affords some important advantages 5 in starting up oil engines and for variable speed injection engines such as are essential for automotive work.

A further feature of this pump resides 10 in the construction details of the discharge valve body 32 and its associated parts. In the construction shown, the stem of the check valve 24 is guided in the body part 32 so that the valve head may accurately align 15 itself with respect to its ground seat, and when closed, the free end of the stem tip 20 may be held out of engagement with the spindle lip 39^a to insure tight seating of the check valve. It is also pointed out that the head portion of the valve 24 can be kept 25 relatively small in size so as to open against a high chamber pressure without undue actuating force. Furthermore the oscillatory movement given the spindle head 38 to open the valve 24 does not in any way interfere with the measured pump displacement of the impelled plunger 19.

Referring now to the action of the control means for regulating the pump and for preventing any oil being sent forth into the power cylinders of a reversing oil engine 30 while the adjusting lever for such control means is set in its stop position. In Fig. 5., the toggle lever 58 is shown as set in such stop position with the control shaft 55 shifted to its furthermost leftward position, thus putting the pin 55^a into the position "d" for which the shaft toe 55^c has disengaged the actuating gear of the discharge valves 24^a and 24^b, as previously explained. 40 In addition, the stanchion 54 will have been raised to ride upon the flat cam face 55^b, which in turn causes the floating lever 53 to hold the bypass valve 47 off its seat for all positions of the plunger part 16^b. It will 45 be seen therefore that when the lever 58 is set in its stop position, this not only prevents opening either of the discharge valves but at the same time breaks the pressure in the pump chamber and thus doubly insures 50 against any oil discharge into the engine cylinders.

The latch notches in the sector 57 correspond to the respective control positions "d" 55 to "g" of the pin 55^a. When the lever 58^a is thrown into the first notch to either side of its aligned or stop position, such movement may be made to throw starting air into the power cylinders and the pin 55^a will then assume the position "e" while the cam disc 26 will again be back in its normal position as shown by full lines in Fig. 2., but the stanchion 54 will still be raised sufficiently to hold open the bypass 47.

As will be more fully explained presently, 60 the starting air control may be made inter-

locking with the further movement of the control lever 58^a such that the starting air is cut off prior to the time that the pump begins to deliver fuel to the engine cylinders. As the lever 58^a is still further moved away 70 from its aligned position, the stanchion 54 then rides upon the curved cam face 55^a and the fuel pump discharge will be correspondingly increased until finally when the pin 55^a reaches its extreme position "g", the 75 stanchion 54 will be riding on the lowest portion of the curved face 55^a. As a consequence the "kick" of the plunger 19 must raise the floating lever 53 to its highest position as shown by dotted lines in Fig. 4., 80 before it lifts the bypass valve 47 off its seat. For any intermediate position of the control shaft 55, the increment of plunger movement that is allowed to discharge oil through either of the valves 24^a and 24^b is 85 accurately fixed by the setting of the control shaft 55. The lever 53 periodically lifts the bypass valve 47 in a definite but alterable point in the path of the impelled plunger part 16^b and thereafter interrupts the 90 further delivery of oil through the particular discharge valve that may have released the impulsion drive.

Furthermore the use of the toggle linkage shown in Fig. 5., represents an element 95 that may be variously incorporated in an engine reverse gear, since its underlying principle is to insure cutting off the oil pump delivery to the engine cylinders whenever the adjusting lever 58^a passes through its stop or aligned position and to gradually increase the pump delivery in a fixed proportion to the movement given the toggle to either side of its aligned position.

As a further modification of the described 105 control features of my fuel pump, it is pointed out that the multiple discharge valve bodies 32^a and 32^b together with their driving mechanism may, with advantage, be entirely detached from the pump block 18 and incorporated with other parts of the engine valve gear in the manner shown in Figs. 6 and 7. These views represent a twin cylinder four-stroke solid injection oil engine, in which the two throw crankshaft 60 110 is provided with a spiral gear 61 for driving the vertical shaft 62 at engine speed. The upper end of this shaft is further provided with a set of miter gears 62^a which also drive the fuel pump 64 at engine speed. In 115 this particular application, the fuel pump proper need only comprise the essential elements shown in Fig. 4., with the addition of the suction valve 22 shown in Fig. 2., while the plural discharge valves 24^a and 24^b required to release the impulsion drive of such pump 64 and the actuating gear for said valves, are placed close up to their respective power cylinders and incorporated as a 120 part of the valve gear of the engine proper 125 130

It will be noted that the vertical shaft 62 is also equipped with a two-to-one bevel gear 63^a that drives the horizontal cam-shaft 63 at half speed with respect to the engine crank shaft. Mounted on the cam shaft 63 is a series of forward and astern cams, each of which co-acts with a suitable and independent bellcrank rocker similar to the part 65, and these cams are adapted 10 to be shifted lengthwise with the shaft 63 in the conventional manner by means of the reverse lever 66. In the position shown in Fig. 7., this lever stands in its mid or stop position, for which the various ahead and 15 astern cams on the shaft 63 are set to straddle their respective bellcrank levers so as not to impart movement to any of the cam actuated valves.

The similar equipment of each of the power cylinder parts is designated by the respective subscripts "a" and "b" as applied to the part numeral. Thus the starting valve 67^a of the one cylinder is actuated by the separate ahead and astern cams 68^a 20 while the axis of the exhaust valve 76^a, as is best shown in Fig. 6., is set inclined with respect to the power cylinder axis and actuated by the separate ahead and astern cams 69^a. Lastly, the combined discharge and 25 spray valve casing 70^a, which functions in a manner similar to the valve 24^a shown in Fig. 2., is also actuated by the separate ahead and astern cams 71^a, either of which cams may at will be thrown into engagement with 30 the tie rod 72^a, which is similar to the rod 31 of Fig. 1., and is intended to be held against the cams 71^a by means of a suitable spring (not shown). As will be seen from Fig. 8., the tie rod 72^a oscillates the 35 spindle 40^a mounted in the casing 70^a and thus positively opens the discharge valve 24^a in a manner identical with that previously described for the similar parts shown in Fig. 3.

The fuel pump 64 is provided with a single plunger 19 and a delivery pipe 73 having distributing branch pipes 46^a and 46^b which are in common communication with the connected pump chamber passages 25 40 and 50 and these branch pipes deliver the pump discharge to the respective control 24^a and 24^b in the casings 70^a and 70^b, which check valves are again made to open against the pressure exerted by the impulsion 45 plunger drive of the pump 64.

The oil after leaving the control of the opened discharge valve 24^a passes a small check valve 74^a on its way to the spray nozzle 75^a which injects into the power cylinder against high compression just prior to the piston approaching its inner dead-center position. It is preferred to offset the spray nozzle from the axis of the drum-shaped combustion chamber 77^a, which 50 chamber encircles the axis of the exhaust

valve 76^a as is indicated in Fig. 8. The effectiveness of the spray action is further facilitated by the inclined position of the exhaust valve 76^a and the manner in which the nozzle is made to inject at right angles 70 to said exhaust valve axis since this allows the spray of the nozzle to be headed toward the piston top without directly impinging against the jacket walls of the cylinder.

Now assuming the four-stroke engine pistons to be in their inner dead center positions as shown in Figs. 6 and 7., and that the eccentric of the fuel pump 64 is set to align with the same so as to operate its spring casing 14 in synchronism with the 80 power piston movements, then in order to start the engine, the reverse lever 66 is pulled out of its mid or stop position into the first latch notch to either side of the stop position depending upon the direction of rotation desired. This serves to put into action the corresponding set of air starting cams 68^a and 68^b and thus successively throws properly timed compressed air on the pistons to start the engine in the customary manner. 90

A further movement of the reverse lever 66 into its last notch will serve to throw said air starting cams out of engagement and subsequently to throw into action the fuel discharge cams 71^a and 71^b. In the 95 mean time the plunger of the fuel pump 64 will have been put into operation and this will send forth pressure impulses into the distributing branch pipes 46^a and 46^b which impulses are properly synchronized with the alternate openings of the pump discharge valves 24^a and 24^b. For the crank settings shown, it is intended that one of the power pistons will be completing its exhaust stroke while the other reaches the end of its compression stroke, the corresponding settings of the valve casings 71^a and 71^b being such that fuel is admitted only into the particular cylinder that is under compression. The other discharge valve does not function 105 therefore until the next following crank revolution, with the result that properly timed fuel is injected first into one and then into the other of the power cylinders.

As stated, the pump 64 is still provided with the control elements 53, 54, and 55 and this admits of simultaneously regulating the pump to both power cylinders by the described action of the single bypass valve 47. 115

It will be seen therefore that by means of this fuel pump and without requiring any substantial modification in the cam shifting arrangement commonly used in the conventional reversing four-stroke engine, the control of the distributed fuel pump discharge 125 valves become centralized in the reverse lever 66. Furthermore the fact that the fuel pump is run at double speed and distributes the oil delivery into two or more power cylinders materially reduces the in- 130

stallation cost and makes for an effective and compact fuel injection means for direct injection oil engines.

The further fact that the release of the energy stored behind the impulsion plunger is under the direct control of any one of the several mechanically operated discharge valves, allows these control elements to be placed at a distance from the pump block and in close proximity to their respective spray nozzles, and further allows such control elements to be independently or selectively operated from the particular engine cylinder parts which the respective discharge valve is intended to serve.

In case the geared type of pump shown in Figs. 1 to 4 inclusive, is to be used for a multicylinder two-stroke oil engine, the pump drive shaft 12 may be run at twice crankshaft speed and the one pump made to feed alternately into any two power cylinders whose cranks are set oppositely, i. e. 180° apart. It will also be apparent that in case it should be preferred to operate the pump drive shaft for a two stroke engine at crankshaft speed, this would eliminate the reduction gears 28^a and 28^b as well as one of the discharge valves 24 and allow the remaining valve to be driven from a cam or an eccentric mounted upon the drive shaft 12.

In addition to providing a simple and compact fuel pumping means for serving a plurality of such cylinder nozzles, the centralized control feature of this pump, which essentially comprises the control shaft 55 for adjusting the common bypass valve 47 as actuated by the plunger movements, also affords another important advantage, especially when applied to the case of marine oil engine drives. Such common control for variably interrupting the distributed pump discharge together with the described means for completely disengaging the discharge valve actuating mechanism, permits of quickly cutting out of service at will a main fuel pump constructed in accordance with Figs. 1 to 5, and in its place, of instantly throwing into service a duplicate or spare fuel pump that is purposely kept running in unison with the main fuel pump. Thus in the event of either pump becoming defective, the duplicate pump may be thrown into service to replace the functions of the other and so maintain the delivery of fuel to the respective power cylinders.

As shown in Figs. 10 and 11, this result can readily be attained with but slight modification in the parts previously described in connection with Figs. 1 to 5. Two independent adjusting levers 58₁ and 58₂ are provided and these are mounted upon a common fulcrum pin 57. The toggle link 59₁ of one such lever is intended to shift the

control shaft 55₁ of the main fuel pump designated as I, while the alternative toggle link 59₂ attached to the other adjusting lever serves to shift the control shaft 55₂ of the duplicate or spare pump II. When both control levers 58₁ and 58₂ are set into their mid or stop position as shown, the respective actuating cams 26₁ and 26₂ will then be shifted into the dotted position indicated in Fig. 2, and thus disengage the actuating gears of both pumps from their respective discharge valves in the manner already set forth.

Furthermore the plural delivery pipes of the main fuel pump are separately cross-connected with the corresponding delivery pipes of the duplicate or spare pump so that one set of such pipes may deliver to their common spray nozzle in the manner indicated in Fig. 11. From the main pump I, the discharge pipe 46^a delivers to the spray nozzle 75^a in the one power cylinder designated as 77^a, while its other discharge pipe 46^b delivers to the spray nozzle 75^b in the second similar cylinder 77^b. From the spare pump, the discharge pipe 46^c likewise delivers to the spray nozzle 75^a through its nozzle check valve 74^c, while the discharge pipe 46^d delivers to the spray nozzle 75^b through its check valve 74^d.

When such duplicate pumps are equipped with the cross-connections indicated, either of the said control levers 58₁ or 58₂ may be moved out of its stop position provided the other is kept therein, and this will cause the particular pump whose control shaft 55 has thereby been shifted to serve the several engine cylinders in precisely the manner previously described, because the pump whose control lever remains in the mid or stop position will be unable to deliver any oil to the engine cylinders through its disengaged discharge valves.

In the event that it is desired to shift from one to the other of said fuel pumps, the displaced control lever of the one pump is first brought back to its mid or aligned toggle position to cut off the oil discharge to the engine cylinders, after which the alternative central lever may be moved out of its mid position and this will immediately cause the spare pump to resume the delivery of fuel to the several power cylinders. If so desired the duplicate control levers 58₁ and 58₂ may be interlocked in such fashion that only one of said levers at a time may be moved out of its respective stop or mid position.

Since the fuel pump constitutes the "heart" of a direct injection oil engine and its proper functioning is absolutely essential to reliable operation, it will be seen that such duplication of this relatively inexpensive but vital adjunct as provided for in the present invention, materially contributes to

the attainment of dependable oil engine service.

In view of the cited modifications, it will be understood that I do not wish to be limited to the particular construction set forth in the given examples of my device, since various changes in structure may be resorted to without departing from the spirit and scope of the present invention or destroying any of the advantages contained in the same, heretofore described and more particularly defined in the appended claims.

Claims.

1. In a fuel pump, an intermediary impulsion drive for the plunger comprising a reciprocating actuating member and a driven member slidably mounted with respect to said actuating member, a primary drive spring thrusting between said members, and a secondary drive spring also thrusting between said members but set to act in opposition to the first named spring.

2. In a fuel pump, an intermediary impulsion drive for the plunger comprising a reciprocating spring casing having shoulder-like lugs near the ends thereof, a plunger drive having a flange-like part slidably mounted with respect to said casing, and drive springs mounted on each side of said drive flange and respectively thrusting against said casing lugs.

3. In a liquid fuel pump comprising a reciprocating actuating part and a driven plunger part slidably mounted with respect to the actuating part, a primary drive spring thrusting between said parts and a secondary spring also thrusting between said parts but set to act in opposition to the primary spring to constitute a floating impulsion drive for the plunger part, means for forcing the plunger part out of its balanced position with respect to the actuating part, and means for subsequently releasing such displaced impulsion drive to impell the plunger onward and discharge liquid fuel from the pump chamber.

4. In a pump provided with a suction valve and a positively opened discharge valve, a reciprocating actuating member and a driven plunger member slidably mounted with respect to the actuating member, a primary spring and a secondary spring acting between said members and each set to thrust in opposition to the other and serving as a floating impulsion drive for said plunger member, means for displacing said plunger member out of its balanced position by the movement of said actuating member, and means for opening said discharge valve to release said impulsion drive and impel the plunger member onward with respect to the actuating member.

5. In a pump having a rotating drive shaft, a reciprocating part actuated from the drive shaft and a driven plunger part

with an impulsion spring drive acting between said parts, means for storing energy within said drive during a portion of the discharge stroke of the reciprocating part, a plurality of positively opened discharge valves each adapted to independently control the release of said energy, a cam and a reduction gear operating said cam at a slower multiple speed ratio with respect to the drive shaft, and means engaging with said cam for successively opening said discharge valves.

6. In a pump comprising a chamber, a suction valve and a fluid supply therefor, a reciprocating actuating part and a driven plunger part, an impulsion spring drive acting between said parts, means for storing energy within said drive during a portion of each discharge stroke of the actuating part, a plurality of positively opened discharge valves each adapted to independently control the release of said energy, means for selectively opening any one of said discharge valves in synchronism with the actuating part movements, a common bypass valve adapted to interrupt the discharge through said opened valve, and control means including a floating lever serving to open said bypass valve in a definite but alterable point in the path of the impelled plunger part.

7. In a pump comprising a reciprocating actuating part and a driven plunger part with an impulsion spring drive acting between said parts, means for storing energy within said drive during a portion of the discharge stroke of the reciprocating part, a positively opened discharge valve controlling the release of said energy to impel the plunger onward, means for opening said discharge valve, a bypass valve adapted to interrupt the flow through such opened discharge valve, a floating lever adapted to open said bypass valve, said lever having an end portion actuated in unison with the plunger, a control shaft means engaging with the other end portion of said lever, and a toggle linkage for adjustably setting the position at which said bypass valve is opened by said floating lever.

8. In a pump comprising a reciprocating plunger, a chamber and a fluid supply therefor, a positively opened discharge valve, means for opening said valve in unison with the plunger movements, a bypass valve between the pump chamber and the fluid supply serving to interrupt the flow through said discharge valve, a floating lever adapted to open said bypass valve said lever having an end portion actuated in unison with the plunger, a control shaft means engaging with the other end portion of said lever, and a toggle link for adjustably setting the control shaft and fixing the position at which said bypass valve is opened, said

toggle link also being adapted to disengage the discharge valve opening means when said toggle link approaches its aligned position.

9. In a fuel pump comprising a reciprocating plunger, a positively opened discharge valve and actuating means for said valve, a control shaft means adapted to regulate the pump discharge, a toggle linkage for adjustably setting the control shaft, 10 said shaft being further adapted to disengage the discharge valve actuating means when said toggle links are moved through their aligned position.

10. In a reciprocating pump comprising a chamber, a plunger and a discharge valve opening inwardly into said chamber, an actuating spindle provided with an annular seat and a lip means adapted to open said valve against chamber pressure, a tubular 20 thrust member surrounding said spindle and engaging with the annular seat thereof to form a rotary hydraulic joint, and means for positively actuating said spindle in unison with the plunger movements.

25 11. In a reciprocating pump comprising a chamber, a plunger and a plurality of discharge check valves opening into said chamber, independent actuating spindles for each of the several valves said spindles 30 being each provided with an annular seat, separate tubular thrust members surrounding each of said spindles and engaging with the respective annular seats thereof, and actuating means for selectively opening any 35 one of said valves against chamber pressure.

12. In a reciprocating pump comprising a chamber, a plunger and a discharge check valve, a body part, an actuating spindle adapted to open said valve against chamber 40 pressure, a head portion for the spindle forming an annular seat therefor, a tubular seat member engaging with the body part and forming a rotary hydraulic joint with said spindle seat, and means for actuating said spindle in unison with the plunger movements.

45 13. In a reciprocating pump comprising a plunger, a pump block having a recessed chamber therein, a discharge valve opening into said chamber, a removable body part having an annular seat surrounding said valve axis adapted to bear against the pump block and enclose said chamber recess, an actuating spindle mounted in said body part serving to open said valve against chamber pressure, and means holding the body part against said block to form a breakable hydraulic joint therewith.

50 60 14. In a directly reversible fuel pump having a drive shaft, and comprising a reciprocating part actuated from said shaft and a driven plunger part with an impulsion spring drive acting between said parts, means for storing energy within said drive 65 during a portion of the discharge stroke

of the reciprocating part, a positively opened discharge valve adapted to control the release of said energy, actuating means for said discharge valve adapted to maintain proper timing of said valve in both 70 the forward and reverse rotation of the drive shaft without need of a reverse gear.

75 15. In a directly reversing fuel pump having a rotating drive shaft, a reciprocating plunger member actuated therefrom, a discharge valve, actuating means for said valve adapted to maintain proper timing of said valve in either the forward or reverse rotation of the drive shaft and means adapted to suitably shift the phase relation 80 of the pump plunger without resort to a reverse gear.

85 16. In a multicylinder oil engine served by a directly reversing fuel pump, said pump comprising a rotating drive shaft and a reciprocating plunger member actuated therefrom, branch pipes distributing the pump delivery to the several engine cylinders, a separate positively opened discharge valve commanding each of said branch 90 pipes, actuating means for said valves adapted to maintain proper timing of the pump when running the drive shaft in either direction, and means to suitably shift 95 the phase relation of the pump plunger without need of a reverse gear.

100 17. In a directly reversible oil engine served by a fuel pump having a drive shaft and a reciprocating plunger actuated therefrom, a positively opened discharge valve, means for actuating said valve in synchronism with the engine piston movements and adapted to properly time the injection of fuel from the pump into the engine cylinder and means serving to bring about a lag in the plunger movement when running in either the forward or reverse direction.

105 110 18. In a fuel pump for a direct injection oil engine, a bypass valve adapted to interrupt the pressure within the pump chamber, a mechanically operated discharge valve, an actuating means for said discharge valve, means adapted to open said bypass valve and to disengage said actuating means serving to discontinue the fuel delivery to the engine cylinder.

115 120 19. In a fuel pump for a direct injection oil engine, control means commanding the full delivery to the engine cylinder, an actuating means for said control means, means to disengage said actuating means while the engine is running, and means including a bypass valve adapted to break the pump pressure while the actuating means is disengaged.

125 20. In a multiplunger fuel pump serving a multicylinder oil engine, separate control means commanding the fuel delivery to respective cylinders, an independent actuating 130

means for each of said control means, and means for selectively disengaging said actuating means to throw the corresponding pump out of service and means including 5 a bypass valve adapted to break the pressure in said pump while its actuating means is disengaged.

In testimony whereof, I have hereunto set my hand this 6th day of December, 1921.

LOUIS ILLMER.
